SHEET SORTING MECHANISM

Edwin G. Harrison, Glen Ellyn, Ill., assignor to
Ditto, Incorporated, Chicago, Ill., a corporation
of West Virginia

Application December 8, 1945, Serial No. 633,623

3 Claims. (Cl. 209—72)

1

My invention relates to sheet sorting and more particularly to the sorting of cards or other flexible sheets and to improved means for carrying out such sorting. The present invention is an improvement over that disclosed and claimed in my Patent No. 2,233,814, dated March 4, 1941, on "Method of and Apparatus for Sorting Cards."

In carrying out the method of sorting cards or similar sheet material members disclosed in the above referred to patent, a slit or other interruption is provided in a margin of a card or similar member of sheet material so as to provide a pair of free edges on opposite sides of the interruption, and suitable means is applied to opposite sides of the cards or other sheet material members for pressing the portions of the sheet on opposite sides of the interruption in opposite directions so that one of the sorting fingers engaging the portion of the sheet material member on one side of the interruption will engage with one face of the sheet material member on one side of said finger and the other side of the next adjacent finger will engage the other side of said sheet material member to thus guide the sheet between the two fingers and eventually into a pocket, tray or other receptacle.

Difficulty has arisen in preventing the interruption, that is thus spread out or opened up by means of the members that press against the sheet in opposite directions, from remaining in such position with one of the free edges thereof out of alignment with the other free edge thereof. If the interruption, in the form of a slit or other opening extending inwardly from the leading margin of the card or other sheet material member, is left in this spread or open position, the tendency will be for the sheet to catch, at the opening thus provided therein, on the edges of the fingers where the same widen out to provide guiding means for the sheet material members to direct them toward the pockets or trays.

It is a purpose of my invention to prevent the difficulty by providing sorting fingers that, instead of having sudden or abrupt increases in width therein, gradually widen from the narrow sorting portions thereof to the guide plate forming portions thereof so as to avoid any abrupt shoulders or other formations along the edges thereof on which the free edge portions of the interruption in the marginal edge of the sheet might get caught to stop the movement thereof or to cause damage to the same.

More particularly it is a purpose of my invention to provide in combination with such fingers having gradually widening portions, cards or

2

other members of flexible sheet material that have an interruption in one of the marginal edges thereof, which becomes the leading edge of the card or other sheet material member while passing through the sorting apparatus, which has at least one of the free edge portions of said interruption extending at an oblique angle to the said marginal edge, and at such an angle to a side edge of a diverging or widening portion of a finger that the inner end portion of the said free edge will engage the sloping side edge of the finger before engagement of the outer end of the free edge at its intersection with the marginal edge therewith. In this manner the edges that have been spread by opening up the interruption in the marginal edge of the card in the manner above referred to are closed up so that there is no possibility of the interruption in the marginal edge of the card or similar member causing the card or similar member to be caught in the position between the fingers so as not to move on into the pocket or tray into which it is to be passed and so that the same will not be damaged by engagement with such side edge of a sorting finger.

The interruptions in the marginal edges of the card are of course to be arranged selectively along the margin of the card, or other member to be sorted, at predetermined points along said marginal edge in accordance with the character of the card or other sheet material member which determines the pocket or tray into which it should be sorted in the same manner that the slits are located in the above referred to patent. However, instead of the slits extending inwardly perpendicularly to the marginal edge the same would extend at such an oblique angle as to have the relationship to the one side edge of a finger above referred to, or instead of having slits, slotted openings would be provided in the marginal edge of a card or sheet material member differentially arranged as above stated with at least one of the free edges produced by such a slot extending at the oblique angle above referred to.

Other objects and advantages of my invention will appear as the description of the drawings proceeds. I desire to have it understood however that I do not intend to limit myself to the particular details shown or described, except as defined in the claims.

In the drawings:

Fig. 1 is a fragmentary view, partly in elevation and partly in vertical section of a sorting apparatus to which my invention is applied;

Fig. 2 is a perspective view of a portion of the

sorting apparatus showing a sheet material member passing into a pocket;

Fig. 3 is a plan view, partly broken away of a plurality of overlapped cards or similar members utilizing one form of my invention;

Fig. 4 is a similar view to Fig. 3 of a modification;

Fig. 5 is a similar view to Fig. 3 of a further modification;

Fig. 6 is a somewhat diagrammatic view showing a pair of the sorting fingers made in accordance with my invention and a card or similar sheet material member made in accordance with my invention in different cooperative relationships to such fingers;

Fig. 7 is a fragmentary perspective view showing a pair of said fingers in the act of guiding one of said sheet material members into position between the same;

Fig. 8 is a section taken on the line 8—8 of Fig. 6;

Fig. 9 is a similar view taken on the line 9—9 of Fig. 6;

Fig. 10 is a similar view taken on the line 10—10 of Fig. 6; and

Fig. 11 is a fragmentary perspective view showing a sheet material member in such position that the obliquely extending free edge of the interruption is beginning to engage with the obliquely extending side edge of one of the fingers.

Referring in detail to the drawings, in Fig. 1 is shown a portion of the sorting machine made in accordance with the invention disclosed in my Patent 2,233,814, but embodying the improvements forming part of this invention. As the general nature of the machine is the same as disclosed in said patent, only the portions are shown in this application that are of importance to the understanding of the present invention.

Suitable guides 10, 11, 12 and 13 are provided, the guides 10 and 11 directing a sheet material member that is moved horizontally along the guide 10 downward between the guide fingers 14 and 15 into the bite of the rollers 16 and 17 which serve to feed the sheet material members to the sorting fingers. The guide members 12 and 13 similarly guide sheet material members that may be fed from vertically above the sorting member into position to pass between the fingers 14 and 15 and to the rollers 16 and 17.

Pivotedly mounted on the pivots 18 and 19 are the curved fingers 20 and 21 which are adapted to be moved from the full line position shown in Fig. 1 to the dotted line position thereof, these fingers pressing against the sheet material member on opposite sides thereof in opposite directions at longitudinally spaced points on the sheet material member near the margin thereof as in the machine disclosed in my above referred to patent, so that if there is a slit, a slot or any other kind of interruption in the marginal portion of the card or other sheet material member that is to be sorted, the portion 22 of such a member on one side of the interruption 23 will pass back of the finger 24 while the other portion 25 on the other side of said interruption 23 will pass in front of the finger 26, adjacent the finger 24, the fingers 24 and 26 defining the entrance to a passage leading into a pocket or tray into which the card 27 having the portions 22 and 25 will pass, this being illustrated in Fig. 7. The card 27 is shown as having passed from the narrow sorting portions 28 to the widened portions 29 of the fingers in Fig. 11, said widened portions gradually tapering from the narrow por-

tions 28 to the much wider portions 30, serving as guide plates to direct the sheet material members being sorted into the trays or pockets 31 into which the same are to pass in accordance with the selection made by means of the sorting fingers.

Generally speaking, the portion of the apparatus above described is similar to that in my above referred patent. However, it will be noted that the sorting fingers have the elongated narrow sorting portions 28 thereof merging gradually into the widening portions 29, the side edges 32 and 33 of the widening portions extending at a very slight angle to the parallel side edges of the narrow sorting portions 28.

After the interruption in the marginal edge of the card or other sheet material member has been spread out or opened out as shown in Fig. 7, there is considerable tendency for the material to remain in this position or in at least a position in which the free marginal edges 34 and 35 of said interruption are slightly out of alignment with each other. If a slit that extends perpendicularly to the leading marginal edge of the card or other sheet material member were provided as shown in my above referred to patent, the tendency would be for the one marginal edge to pass on one side or face of the finger 28 that is shown to the left of the slot or interruption in Figs. 6, 7 and 11, while the other free marginal edge thereof would tend to pass on the other side of said edge 33 of the widening portion 29 of said finger which would eventually result in the card or other flexible sheet material member becoming caught on the finger, thus interfering with the proper passage of other cards or similar sheet material members into the pocket or tray into which the same are to be sorted, or would cause tearing of the sheet material member if sufficient force has been exerted thereon to cause such tearing to take place in passing it downwardly between the fingers.

In order to avoid this difficulty I have provided an interruption in the marginal edge of the sheet material member which serves the same purpose as the slit above referred to, but in which the marginal edge 35 related to the obliquely extending edge 33 of a widening portion 29 in the manner above referred to extends at an oblique angle to the marginal edge of the sheet. Said oblique angle is such that the inner end 36 of the interruption, which is shown in the form of an obliquely extending slit in Figs. 2, 3, and 6 to 11 inclusive, will engage the marginal edge 33 of the widening portion 29 of said finger first.

The result of this is, that, due to the fact that the said marginal edge engages the slit at the inner end thereof where the material on opposite sides of the slit are substantially in alignment, said widening portion of the finger through action of its obliquely extending edge 33 will cam down or flatten out the edge portion 35 to align it with the edge portion 34 and thus by the time that the outer end 37 of said edge 35 engages the edge 33, there will be no possibility of said edge 35 getting on the opposite face of the widened portion 29 to that on which the edge portion 34 lies.

In Fig. 6 the slit 23 is shown as being partly open at the upper portion of said finger with the ends of the finger 28 in proper engagement therewith to accomplish the sorting of the card or similar sheet material member into the proper pocket or tray. In the dotted line position shown next to the full line position at the top of Fig. 6, the end

36 of the slit has already passed the edge 33 so as to start the closing of the slit 23 and in the dotted line position shown near the bottom of said figure, said slit is completely closed and has entirely passed back of the wide portion of the finger 29. The relative position of the fingers and the edge portions of the card when first entering between the fingers is shown in section in Fig. 8 while in Fig. 9 the card is shown with the two portions 22 and 25 on opposite sides of the slit in substantial alignment with each other at the point where the section is taken, which is at a point at which the marginal edge 33 has already passed the end 36 of the slit. In Fig. 10 the two portions 22 and 25 are shown as being completely aligned, the slit 23 being completely closed as the edge 33 has passed entirely beyond or over the slit and both the portions 22 and 25 of the marginal part of the sheet material member or card 27 are on the same side of the member 29, one member 29 being completely on one side of the sheet and the other member 29 being on the other side thereof so that there is no possibility that the card or other sheet material member might catch on the member 29. In Fig. 11 the position of the marginal edge of the card is substantially as shown in the first dotted position shown in Fig. 6 with the inner end 36 of the slit 23 just starting to engage with the inclined edge 33 of the widening portion 29 of the one finger 28.

It will be noted upon reference to Fig. 6 that in order for the inner end 36 of the slit 23 to engage first with the marginal edge 33 of the left finger 28 in Fig. 6 the slit 23 must extend at an oblique angle to the leading marginal edge of the card or similar sheet material member that is being sorted that is less than the angle of the edge 33 to said leading edge.

In using my invention to sort a plurality of different cards, such as illustrated in Fig. 3, the cards being shown overlapped so as to expose only the marginal edges thereof except for the uppermost card, the slits are arranged with their ends that intersect the margin, spaced at predetermined points along said margin to determine a particular selection in accordance with the position of the slit provided on a particular card or set of cards. While cards are shown in Fig. 3 and also in Figs. 4 and 5 as having the interruption in the marginal edges thereof in a somewhat regular or stepped arrangement, this is merely for purposes of illustration, as the particular position of the slits or other interruptions in the cards would vary both in spacing and position from that shown in the drawings and would not, of course, come in any regular order relative to each other in entering the sorting machine as cards in the same position may follow each other or the slits may be in widely scattered positions in succeeding cards without in any way having any effect on the successful operation of the invention.

Thus in Fig. 3 a plurality of cards 41, 42, 43, 44 and 45 are shown as having the obliquely extending slits 46, 47, 48, 49 and 50, which correspond in direction to the oblique angle at which the slit 23 extends, but having various positions along the marginal edges of the various cards or other sheet material member, and as a result passing between different fingers to be sorted into different trays or pockets 31.

Instead of providing obliquely extending slits, such as the slits 23 the interruptions can be made in the form of slots, such as slots 51, 52, 53 and 54 shown as being provided respectively in the cards or similar sheet material members 55, 56, 57

and 58 respectively shown in Fig. 4, said slots having one of the free edges 50 thereof extending at an oblique angle corresponding substantially to that of the slit 23 and having the other free edge 60 thereof extending perpendicularly to the leading marginal edge of the card or other sheet material member.

While the free edge 60 can extend at right angles to the marginal edge of the card or other sheet material member to which the slot is provided, preferably both marginal edges of the slot extend at an oblique angle and preferably the angle at which these extend is an acute angle and preferably a rather sharp acute angle, as that will aid in aligning the opposed edges of the slot at the inner end thereof as with the slit 23 above described.

The inner end of the slot 51 is indicated by numeral 61 and the slot 51 will first pass under the edge 33 of the one widening portion 29 just as in the case of the slit 23. Slots 51, 52 and 53 are all made in a similar manner, being merely in a different position along the margins of the cards to sort the cards into different pockets or trays.

A plurality of cards having slots therein having both the marginal edges extending at an oblique angle to the leading marginal edges of the cards or sheet material members is shown in Fig. 5, the cards 62, 63, 64 and 65 being shown as being provided with obliquely extending tapering slots 66, 67, 68 and 69, the marginal edges 70 and 71 of said slots extending at an oblique angle to the marginal edge of the card or sheet material member and both inclining in the same direction, and the inner ends 72 of the said slots engaging the edges 33 of the fingers first in the same manner as the slits 36 engage the edges 33. All of the slots 66, 67, 68 and 69 are made in the similar manner, but have different positions along the marginal edges of the cards to provide for the sorting thereof in the different trays or pockets.

By using any of the forms of interruption described in the marginal edge of the card or sheet material member that is the leading edge, when such card or member is passed into the sorting mechanism, the result is accomplished that said cards or other sheet material members will not catch on the widening portions of the sorting members and will not be damaged by the inclined edges thereof.

What I claim is:

1. The combination with a pair of guide plates each having a narrow flat sorting finger thereon, said fingers being arranged side by side in parallel spaced relationship, each of said fingers gradually widening at a point spaced from the ends thereof to provide obliquely extending side edges on each thereof extending at an acute angle to each other, of pieces of sheet material each having an interruption in a marginal edge thereof to provide a pair of free edges extending inwardly from said marginal edge, and means for pressing the portions of a sheet on opposite sides of said interruption in opposed directions to cause the portion thereof on one side of said interruption to engage one face of one of said sorting fingers and that portion on the other side of said interruption the opposed face of the other of said fingers.
2. The combination with a pair of flat sorting fingers arranged side by side in parallel spaced relationship, said fingers having long narrow end portions having substantially parallel side edges

and gradually widening portions extending from said narrow end portions having diverging side edges extending at an acute angle to the longitudinal axis of said end portions and to each other, of pieces of sheet material each having an interruption in a marginal edge thereof to provide a pair of free edges extending inwardly from said marginal edge having at least one of said free edges extending at an acute angle to said marginal edge such that the inner end of said free edge engages the diverging side edge of one of said fingers before any other portion of said free edge engages the same.

3. The combination with a pair of flat sorting fingers arranged side by side in parallel spaced relationship, said fingers widening at a point spaced from the ends thereof, of pieces of sheet material each having an interruption in a marginal edge thereof, said edges being the leading edges of said pieces of sheet material as the same move into engagement with said sorting fingers, said interruption providing a pair of free edges extending inwardly from said marginal edge, at least one of said free edges extending at an oblique angle to said marginal edge, and means

for pressing the portions of a sheet on opposite sides of said interruption in opposed directions to cause the portion thereof on one side of said interruption to engage one face of one of said sorting fingers and that portion on the other side of said interruption the opposed face of the other of said fingers, the widening portions of said fingers having side edges extending at an obtuse angle to the leading marginal edge of said piece of sheet material less than that of said obliquely extending free edge.

EDWIN G. HARRISON.
